UNITED STATES PATENT OFFICE

HENRY L. GRIGGS, OF PELHAM, NEW YORK, ASSIGNEE, BY MESNE ASSIGNMENTS, TO
WM. H. BRISTOL TALKING PICTURE CORPORATION, OF WATERBURY, CONNECTICUT,
A CORPORATION OF CONNECTICUT

COMBINED ELECTRICAL PHONOGRAPH AND RADIOCABINET

Application filed June 13, 1925. Serial No. 36,854.

The invention relates to cabinets for sound reproducing apparatus, more particularly a phonographic unit and a radio receiving unit, which are housed thereby.

5 The invention has for its object, in a cabinet of this character, the provision of a sound emitting member or electrical loud speaking receiver suitably housed therein and which receiver shall be common to both of the units, 10 the phonographic reproducing unit to this end being of the electrical type embodying a microphonic transmitter arranged to be associated with the usual turntable of said phonographic unit and all being housed in 15 a suitable compartment of the cabinet. A further compartment is provided for the radio receiving unit and is designed to accommodate any standard or special type thereof; and is of such proportions that the cabinet 20 is not restricted to one particular make or style of radio apparatus. A further object of the invention consists in means for automatically disconnecting one of said units from the loud speaking receiver when it is 25 desired to operate the other. The invention has for a still further object to increase, if desired, the volume of the sound from the phonograph apparatus.

The nature of the invention, however, will 30 best be understood when described in connection with the accompanying drawings, in which—

Fig. 1 is a front elevation of the novel cabinet of the upright style, with portion 35 broken away.

Fig. 2 is a vertical transverse section thereof.

Fig. 3 is a front elevation of a console type of cabinet.

40 Fig. 4 is a detail fragmentary view illustrating the operation of the switching mechanism.

Fig. 5 is a wiring diagram of the electrical connections involved.

45 Referring to the drawings, more particularly to Figs. 1 and 2 thereof, 10 designates a suitable cabinet for housing the various instrumentalities hereinafter set forth and may be supported upon legs 11, the cabinet shown 50 in said figures being of the upright type. As

shown, the particular cabinet is provided with four portions separated by suitable dividing walls, the uppermost portion containing a loud speaker compartment 12 and the front of which is closed over in the usual manner by grill work, and thru which the sound emitted by a loud speaker 13 is projected. Upon either side of said compartment 12 may be provided record compartments 14 for storing phonographic records in manner well understood.

Immediately beneath the aforesaid compartments is located the phonograph portion comprising a compartment 15 in which is mounted a rotatable turn-table 16 operated from an electric motor 17 under the control of a switch member 18. Associated with this turntable is a microphonic transmitter 19 carrying a stylus 20 adapted to operate in the grooves, of a record 21 carried by said turn table, as is well understood. Upon either side of the compartment 15 are located further compartments 22 and 23 for volume control apparatus for the phonograph device, the control being effected thru rotating suitable knobs 24 and 25 respectively and accessible when the drop front 26 is lowered.

Beneath the said phonograph and control compartments is located a compartment 30 with drop front 31, said compartment being of sufficient capacity to receive and house a radio cabinet 32 which may be of any well-known or special design, suitable connections (not shown) being provided within the cabinet as for antenna and ground and the usual A and B-batteries. The latter may be housed in a further compartment 35 located beneath the radio compartment 30 and closed by a drop front cover 36, an A-battery 37 being indicated and a plurality of B-batteries 38.

90 In Fig. 3 a console type of cabinet is disclosed with loud speaker compartment 40 and adjacent phonographic compartment 41 with volume control compartment 42 immediately beneath the latter, the same being located at the uppermost portion and the loud speaker compartment being closed by a door 43 and the phonographic and volume control compartments by a door 43'. In order to afford convenient access to the turntable for replac-

ing records, the lid or top 44 may be constructed to lift up as by hingedly connecting the same to the phonograph compartment.

Beneath the aforesaid compartments is located the radio compartment 45, and immediately beneath the same the battery compartment 46, as in the previously described embodiment.

In accordance with the invention, the loud speaker device 13 is intended to serve as an electrical receiver common to both the phonograph unit hereinbefore described and the radio unit; and to this end, provision is made for cutting off automatically the one unit from the speaker when the other is put into use. Any suitable means for accomplishing this control of the circuit may be provided. For example, a spring urged plunger type of switch 50, as shown more particularly in Fig. 4, may be secured to a wall of one of the compartments, for example the radio compartment, the plunger 51 thereof being adapted to cooperate with the door thereof so that when the latter is in the lowered position shown in Fig. 2, or the dotted position, Fig. 4, the plunger will be extended, as indicated in dotted position Fig. 4, and the circuits thru the switches respectively closed and opened and vice versa. That is to say, when the cover of a radio compartment is lowered, electrical connection is made between the radio set therein and the loud speaker while simultaneously therewith the circuit between the microphone transmitter or power amplifier circuit and the said loud speaker is opened. It will be appreciated that if desired provision may also be made in similar manner to cut off the loud speaker from the phonograph portion when the door or lid for its compartment is closed; but generally this will not be required. By the aforesaid arrangement there can be no confusion of sounds thru simultaneous operation of both units.

The general arrangement of the circuits involved is indicated in Fig. 5 of the drawings, the transmitter 19 being of the differential type and operated from the A-battery 37, although it will be understood that an independent battery may be employed for this purpose if desired. It is preferred to include between said transmitter and the loud speaking receiver 13 a filter device 55 for eliminating to a large extent extraneous noises, for example a device of the character set forth in U. S. Letters Patent No. 1,490,764 to W. H. Bristol. A rheostat 56 also is included in the battery circuit to the transmitter to control the volume, being operated by the knob 25.

When it is desired to increase the volume beyond that possible thru the resistance variation, a power amplifier 57 is arranged to be connected to the transmitter output; and, to this end, the said amplifier is connected

to the B-battery 37 and arranged to be connected with the A-battery 37 by further turning of the knob 25, the power amplifier itself being controlled by the knob 24. In order conveniently to connect the transmitter output to the said amplifier, a double-pole double-throw switch 58 is included in the connection to the loud speaker 13, and this switch may be arranged either for independent manual control or be operated directly thru the rotation of knob 25. The switch 50 with double contact is shown connected in the loud speaker circuit in manner to cut in one or the other of the two units, the phonographic unit being indicated as in circuit 80 and with power amplifier disconnected.

By the contacts of the switch 50, therefore, a circuit may be established between the lower switch arm and the outer portion of the plunger element, that is to say the portion to the left of the insulation at 50. This corresponds to the closed position indicated at the upper contact 50 of the wiring diagram. The other circuit is established when the plunger is projected outwardly, as in the dotted position Fig. 4, the conducting portion at 51 to the right of the insulation then having moved outwardly to a position beneath the upper of the contact arms and establishing the other circuit or at the lower of the contacts 50, Fig. 5. Normally, and when the door is in the closed position, the plunger is forced inwardly, as shown in full lines in Fig. 4, so that the said upper arm rests upon the insulation portion of the plunger and opens the circuit conforming to the showing at the lower contact 50, Fig. 5 of the drawings.

I claim:—

1. A musical cabinet embodying a casing providing a phonograph compartment, a turntable therein and an electric reproducer unit associated therewith; a radio compartment, and a radio receiving unit therein; a loud-speaking receiver common to both units, and circuits thereto from said units; a movable cover member for one of the compartments to render its contained unit normally inaccessible; and switch mechanism operable by movement of the said cover member for controlling the circuits to the loud-speaking receiver of the particular unit within the compartment and oppositely controlling the circuit of the other unit to the receiver.

2. A musical cabinet embodying a casing providing a phonograph compartment, a turntable therein and an electrical reproducer unit associated therewith; a radio compartment, and a radio receiving unit therein; a loud-speaking receiver common to both units, and circuits thereto from said units; means to close the respective cabinets; and means controlled thereby for controlling the circuits to the loud-speaking receiver to complete the one circuit thereto upon opening a corresponding cabinet and simultaneously

opening the circuit from the other cabinet thereto.

3. A musical cabinet embodying a casing providing a sound compartment, and a loud-speaking receiver therein; a phonograph compartment, a turntable therein, and a microphone transmitter associated therewith; electrical connections from said transmitter to the loud-speaking receiver; a radio compartment, a radio receiving set therein, and electrical connections from same to said loud-speaking receiver; a movable cover for one of the compartments; and switch mechanism associated therewith for closing the electrical connection between the one of the said units and the loud-speaking receiver, and to open simultaneously the circuit between the other unit and the said loud-speaking receiver.

4. A musical cabinet embodying a casing providing a sound compartment, and a loud-speaking receiver therein; a phonograph compartment, a turntable therein, and a microphone transmitter associated therewith; electrical connections from said transmitter to the loud-speaking receiver; and an intermediate volume control device included therein; a radio compartment, a radio receiving set therein, and electrical connections from same to said loud-speaking receiver; a movable cover for one of the compartments; and switch mechanism associated therewith for closing the electrical connection between one of said units and the loud-speaking receiver when said cover is opened and to open simultaneously the circuit between the other unit and the said loud speaking receiver.

5. A musical cabinet embodying a casing providing a sound compartment, and a loud-speaking receiver therein; a phonograph compartment, a turntable therein, and a microphone transmitter associated therewith; electrical connections from said transmitter to the loud-speaking receiver, and an intermediate volume control device included therein and comprising thermionic amplifier apparatus; a radio compartment, a radio receiving set therein, and electrical connections from same to said loud-speaking receiver; a movable cover for one of the compartments; and switch mechanism associated therewith for closing the electrical connection between one of said units and the loud-speaking receiver when said cover is opened and to open simultaneously the circuit between the other unit and the said loud-speaking receiver.

In testimony whereof I affix my signature.

HENRY L. GRIGGS.
